[57] **CLAIM**

The ornamental design for a pedestal closure assembly, as shown and described.

DESCRIPTION

FIG. 1 is a perspective view of the pedestal closure assembly of the present invention;

FIG. 2 is a back view of the pedestal closure assembly of FIG. 1;

FIG. 3 is a front view of the pedestal closure assembly of FIG. 1;

FIG. 4 is a right side view of the pedestal closure assembly of FIG. 1, the left side view being a mirror image;

FIG. 5 is a top plan view of the pedestal closure assembly of FIG. 1; and,

FIG. 6 is a bottom plan view of the pedestal closure assembly of FIG. 1.

The broken lines in FIGS. 1 through 6 are used to show visible environmental structure, and form no part of the claimed design.
